US00D988519S

(12) **United States Design Patent** (10) **Patent No.:** **US D988,519 S**
(45) **Date of Patent:** **** Jun. 6, 2023**

(54) **PATCH**

(71) Applicant: **NYXOAH S.A.**, Mont-St-Guilbert (BE)

(72) Inventors: **Yoel Ben Yosef**, Givatayim (IL); **Ronen Adimor**, Ness Ziyona (IL); **Roi Moshe Tsukran**, Ramat Gan (IL)

(73) Assignee: **NYXOAH S.A.**, Mont-St-Guilbert (BE)

(**) Term: **15 Years**

(21) Appl. No.: **29/706,981**

(22) Filed: **Sep. 25, 2019**

Related U.S. Application Data

(63) Continuation-in-part of application No. 29/596,273, filed on Mar. 7, 2017, now Pat. No. Des. 866,769.

(57) **CLAIM**

The ornamental design for a patch, as shown and described.

DESCRIPTION

FIG. 1 is a top, perspective view of a patch; FIG. 2 is a side elevational view of the patch shown in FIG. 1, with the other side elevational view being a mirror image thereof;

FIG. 3 is a front elevational view of the patch shown in FIG. 1, with the back elevational view being a mirror image thereof;

FIG. 4 is a top plan view of the patch shown in FIG. 1; and, FIG. 5 is a bottom plan view of the patch shown in FIG. 1. The features shown in broken lines do not form part of the claimed design.

1 Claim, 4 Drawing Sheets
